UNITED STATES PATENT OFFICE.

NICHOLAS A. PEOT, JR., OF GREEN BAY, WISCONSIN.

FOOT-REST FOR RADIATORS.

1,143,859.

Specification of Letters Patent. Patented June 22, 1915.

Application filed August 24, 1914. Serial No. 858,303.

To all whom it may concern:

Be it known that I, NICHOLAS A. PEOT, Jr., a citizen of the United States, residing at Green Bay, in the county of Brown and State of Wisconsin, have invented certain new and useful Improvements in Foot-Rests for Radiators, of which the following is a specification, reference being had to the accompanying drawings.

10 This invention relates to foot rests, and particularly to foot rests for use in connection with radiators.

An object of this invention is the provision of a foot rest for radiators which may 15 be quickly and easily attached to or detached from the radiator.

A further object of this invention is the provision of a foot rest for radiators or the like in which the foot supporting rail is 20 pivotally connected to the radiator, so that the rail may be swung upwardly against the radiator when the rail is not desired for use.

With these and other objects in view, my invention consists in the novel construction, 25 combination, and arrangement of parts to be hereinafter more fully described, claimed, and illustrated in the accompanying drawing, in which—

Figure 1 is a perspective view of my improved foot rest showing the same in a position for use; Fig. 2 is a perspective view of one of the clamps used in connection with the rest; Fig. 3 is a perspective view of one of the arms for supporting the foot rail; 35 and Fig. 4 is an elevational view of one of the clamping bolts for securing the clamps to the radiator.

Referring more particularly to the drawing, the numeral 1 designates the tubes of 40 the radiator of any ordinary construction, to which my improved rest is adapted for connection.

The foot rest includes a pair of clamps, each of which consists of a pair of crossed 45 clamping levers 2 which are curved at one end to provide jaws, the handle end of each lever being provided with an eye 4 at its extremity. One of the levers of each pair is provided with an offset portion 5 intermediate of its ends to provide a seat for the other lever, whereby the levers of each pair are pivotally engaged upon each other.

Disposed through the eye 4 of each pair of levers is a clamping bolt 6, each of the 55 bolts having a shoulder 7 formed thereon adjacent the head of the bolt, and the free

ends of the bolts being threaded as at 8 for the reception of nuts 9.

When it is desired to clamp the levers 2 to spaced tubes of the radiator, the bolts 7 are passed through the eyes 4 of the levers until the shoulders 7 engage one of the eyes of each pair, whereupon the nuts are threaded upon the threaded extremities of the bolts to engage against the other eye of each pair to tightly clamp the jaws 3 of the levers around the tubes.

The numeral 10 designates the foot rail of my improved device, and connected to the rail adjacent its ends are laterally extending supporting arms 11, each of the arms having a curved recess 12 formed in its lower edge, the recesses being adapted for engagement with the clamping bolts 6. The portions of the arms from the recesses to their inner extremities are of a length sufficient to engage the tubes, the upper edges of the arms engaging the offset portions 5 of the levers, whereby the downward movement of the outer ends of the arms is limited when the arms are in a horizontal plane.

From the above description taken in connection with the accompanying drawing, it will be seen that the clamping levers may be 85 quickly and easily connected to the tubes of the radiator, and that when the levers are disengaged from the radiator, the same may be placed one above the other so that the size of the device is reduced for convenience 90 in storing. It will also be seen that the foot rail 10 may be either moved upwardly to rest against the radiator when the rail is not desired for use or that the same may be entirely removed from the radiator by disengaging the recesses 12 from the bolts 6.

To brace the foot rail 10 when the same is in position for use, a pair of sectional supporting posts is loosely connected thereto, each of the posts comprising a rod 12 having an eye 13 at its upper end for loose engagement with the rail 10, the lower end of the rod being threaded for engagement in the upper end of a tubular rod 14 which is provided at its lower end with an enlarged 105 base 15. As the supporting posts are loosely mounted on the rail 10 by the eyes 13, it will be seen that the weight of the posts normally maintain the same in a vertical position, so that when the rail 10 is swung 110 upwardly to rest against the radiator, the posts will be disposed closely adjacent the

radiator, and when the rail is swung downwardly to a position for use, the posts will retain their vertical positions, so that the base 15 will engage the floor.

5 By the provision of the sectional posts the same may be elongated or shortened dependent upon the height at which the clamps are secured to the radiator, the posts being lengthened or shortened by merely 10 rotating the tubular sections 14 upon the threaded portions of the rods 12.

Having thus fully described my invention, what I desire to claim and secure by Letters Patent is:—

15 1. A foot rest for radiators and the like comprising a pair of spaced clamps each comprising a pair of crossed clamping levers curved at one end to provide jaws, clamping bolts connecting the other ends of each pair 20 of levers to hold the jaws in closed position, supporting arms loosely mounted upon said clamping bolts, and a foot rail carried by said supporting arms.

2. A foot rest for radiators and the like comprising spaced clamps, each of the clamps consisting of a pair of crossed levers curved at one end to provide jaws, one of the levers of each pair intermediate of its ends being formed with an offset portion 30 to provide a seat for the other lever whereby the levers are pivotally engaged upon each other, the outer end of each lever being provided with an eye, a clamping bolt disposed through the eye of each pair of levers, each 35 of the bolts having a shoulder formed there-

on for engagement against one of the eyes of each pair, means mounted on the other end of each bolt to close the jaws of the clamps, a supporting arm loosely mounted upon each bolt, and a foot rail carried by 40 said supporting arms.

3. A foot rest for radiators including a pair of spaced clamps, each of said clamps including a pair of crossed levers, one of said levers being offset intermediate its 45 length to receive the other lever, whereby the two levers are pivotally connected, and a clamping bolt connecting the outer ends of the levers, whereby the same may be drawn toward each other to clamp the jaw portions 50 of the levers about the radiator, a supporting arm pivoted on the bolt of each clamp, and a foot rail supported by the arms.

4. A foot rest for radiators including a pair of spaced clamps adapted to be engaged with the sections of the radiator, each of said clamps including a pair of crossed levers, an arm swingingly attached to the outer ends of the levers of each clamp, the inner end of each arm being engageable 55 with the levers at the intersection of these members, and a foot rail carried by the outer ends of the arms.

In testimony whereof I hereunto affix my signature in the presence of two witnesses.

NICHOLAS A. PEOT, JR.
